US0D1068419S

(12) **United States Design Patent** (10) **Patent No.:** **US D1,068,419 S**
(45) **Date of Patent:** **** Apr. 1, 2025**

(54) **WRENCH**

(71) Applicant: **Yuting Chen**, Shenzhen (CN)

(72) Inventor: **Jinman Shen**, Taizhou (CN)

(73) Assignee: **Yuting Chen**, Shenzhen (CN)

(**) Term: **15 Years**

(21) Appl. No.: **29/982,873**

(22) Filed: **Jan. 8, 2025**

(30) **Foreign Application Priority Data**

Sep. 19, 2024 (CN) 202430597420.7

(51) **LOC (15) Cl.** **08-05**

(52) **U.S. Cl.**

USPC **D8/21**

(58) **Field of Classification Search**

USPC D8/24, 107, 21, 22, 25; D10/83

CPC B25B 23/1425

See application file for complete search history.
